UNITED STATES PATENT OFFICE.

MARK REEVE, OF PARALTA, IOWA.

IMPROVEMENT IN WATER-FEEDERS FOR STEAM-BOILERS.

Specification forming part of Letters Patent No. 146,145, dated January 6, 1874; application filed November 4, 1873.

To all whom it may concern:

Be it known that I, M. REEVE, of Paralta, in the county of Linn and State of Iowa, have invented certain new and useful Improvements in Water-Feeder for Steam-Boilers; and I do hereby declare the following to be a full, clear, and exact description of the invention, such as will enable others skilled in the art to which it pertains to make and use it, reference being had to the accompanying drawings, which form part of this specification, in which—

Figure 1 is an elevation, showing the parts of the invention and connections. Fig. 2 is a longitudinal section of the valve and chambers. Fig. 3 is a perspective view of the feeder and connecting-pipes.

Like letters in the different figures indicate like parts.

My invention consists of an automatic boiler-feeder, as hereinafter described.

A represents a hollow globe. B is a safety-tank or reservoir. C is a pipe leading from tank B to valve-case T. D is a water-pipe leading from valve-case T to boiler K. E is an exhaust-pipe connecting with chamber S, to allow the steam to escape when pipe J is closed. F is a steam-pipe leading from the boiler to the valve-case T. G is an adjustable weight attached to a lever, L. H is a water-pipe leading from the valve-case to the globe A. J is a steam-pipe leading from the valve-case to the globe. L is a lever attached to the plug of the valve-case T, and sustains the weight G and globe A. N is a packing-nut on the end of the valve-case. O is the plug fitting perfectly in case T, and S is a steam-chamber, and W a water-chamber in the plug O.

The water descends from tank B, through pipe C, into chamber W, and from thence, through pipe H, into the globe A. The weight,

being properly adjusted on the lever L when the globe is nearly or quite full, it descends to the position indicated by dotted lines and raises the weight, as shown in Fig. 1. This movement of the globe turns the plug O in its seat, closing pipe C, and stopping the flow of water from the tank, and at the same time opens the steam-pipe F into the chamber S, and allows the steam to pass through pipe J into the top of the globe A, thus equalizing the pressure, and the water in globe A passes back through chamber W, along pipe D to the boiler. When the water is nearly or quite out of the globe, the weight G descends, bearing up the globe, reopening pipe C, and closing the steam-pipe F, and the water again flows into the globe till it descends, as before. This operation continues until the water in the boiler is on a level with the water in globe, when it is in its lowest position; and when the water in the boiler becomes lower than the level of the water in the globe, the water commences again to flow from the globe to the boiler, and the operation above described will be repeated, thus automatically supplying the boiler with water, and preventing the liability of the water being exhausted in the boiler.

What I claim as new, and desire to secure by Letters Patent, is—

The oscillating feeder A, in combination with boiler K, adjustable weight and lever G, L, water and steam pipes C, D, E, F, H, and J, and self-acting valve-case T and plug O, substantially as and for the purposes described.

In testimony that I claim the foregoing I have hereunto set my hand.

MARK REEVE.
